UNITED STATES PATENT OFFICE.

PAUL F. COX, OF CHICAGO, ILLINOIS.

ADDRESSING MECHANISM (SLUG).

1,344,384.

Specification of Letters Patent. Patented June 22, 1920.

Application filed October 16, 1919. Serial No. 331,152.

To all whom it may concern:

Be it known that I, PAUL F. Cox, a citizen of the United States, residing at Chicago, in the county of Cook and State of

5 Illinois, have invented certain new and useful Improvements in Addressing Mechanism (Slug); and I hereby declare that the following is a full, clear, and exact description thereof, reference being had to the 10 accompanying drawings, which form part of this specification.

This invention is a novel mechanism for addressing articles, such as envelopes, packages, newspapers, and the like, by printing 15 thereon or applying to each of such articles the address of the person for whom it is intended.

The invention is adapted for use in connection with printing presses and other 20 mechanisms handling articles so that when the articles are delivered they are also addressed and ready for mailing.

The invention provides an addressing 25 mechanism which is particularly designed for attachment to a newspaper printing press and adjacent the folder former so as to print different addresses upon successive impressions or newspapers as they pass down 30 the former, and preferably before the web is severed, and before the printed sheets pass into the folding rolls.

When the novel mechanism is attached to an ordinary printing press or newspaper 35 press the web handling mechanism of the press serves as the feeding and delivery mechanism for the addressing attachment and the power mechanism of the press serves as the actuating means for the addressing 40 mechanism. The addressing mechanism is compact and economical, and can be readily adapted for and applied to any of the standard makes of web printing machines.

I do not consider the invention in its 45 broader aspects restricted to any specific construction of the addressing mechanism *per se*; but will explain the same with reference to the accompanying drawings which illustrate one practical embodiment and application of the invention and will enable others skilled in the art to readily adapt and use the invention. The essentials of the invention and novel combinations of parts and novel features of construction, for 50 all of which protection is desired, are set forth in the claims.

In said drawings, Figure 1 is a front elevation of an addressing mechanism attached to the frame of a printing press in operative relation to the folder former. 60

Fig. 2 is a top plan view.

Fig. 3 is an enlarged side elevation of such addressing mechanism.

Fig. 4 is a detail top plan view of the feed chute and slug ejecting devices. 65

Fig. 5 is a diagrammatical view of web printing mechanism, web folding mechanism, and the addressing mechanism operating upon the web at the former.

The operative parts of the addressing 70 mechanism are mounted in a suitable frame, the particular form of which is not material, provided it affords proper support and bearings for the operative parts of the addressing mechanism.

In the present instance the addressing mechanism is shown as designed to use individual printing members of any suitable kind—and shown as slugs or type metal bars 75 A each bearing the name and address or other indicia of the addressee. These slugs are supplied from a feed chute 2, which is supported upon the frame 1 in vertical position and can be supplied with the slugs from loading galleys such as are commonly 80 used in the so-called addressing machines now on the market, so that the feed chute may be supplied with these slugs and replenished therewith without stopping the operation of the machine until all the addresses 85 have been printed. 90

The lower end of the chute 2 rests upon a plate 2^a on which is slidably mounted an ejector slide 3, that operates through suitable slots in the front and rear walls of the chute and is adapted to successively eject the slugs from the chute, the slide ejecting the slugs one at a time in the usual manner. In the construction shown the slugs are 100 ejected base first, type outermost, from the chute 2, and to prevent injury to the type the end of the ejector may be recessed as shown, so that it only engages the slugs near the ends thereof without striking the type 105 surfaces.

The slide may be operated by any suitable means. As shown it is reciprocated by means of a crank rod 3^a pivotally connected with the slide and with a crank pin 3^b attached to a rotatable slug carrier 4, keyed 110 on a shaft 4^b, which is journaled in suitable

bearings in the frame 1, and rotated as hereinafter explained.

The slug is ejected from the chute 2 onto spaced fingers 2^c attached to or formed on the inner end of the plate 2^a and is supported by such fingers in position to be taken by radially projecting fingers 4^c on the carrier 4, the fingers 4^c passing between the fingers 2^c and picking up the slug lying thereon as the carrier 4 rotates with the shaft 4^b. The fingers 4^c may be formed integral with, or attached to the carrier 4.

The slug taken from the fingers 2^c by the carrier fingers 4^c may be securely held on the carrier 4 by any suitable devices. As shown a gripper 5 is provided having a head 5^a adapted to engage the adjacent end of the slug and press it tightly against a shoulder 4^f on the finger 4^c at the opposite side of the carrier (see Fig. 3). This gripper is shown as pivoted on lugs 4^e projecting from the side of the carrier 4; and as slotted to accommodate the crank pin 3^b. The gripper may be normally held in closed position by means of a spring 5^e interposed between the end 5^b of the gripper, (opposite its head 5^a), and carrier 4, as shown; which spring may be seated in a recess in the member 4, as shown.

30 The gripper is opened and closed at the proper times in its rotary movement by suitable means. As shown a rod 5^f is connected with or engages the gripper near its head 5^a and extends through a hole in the carrier 4 and projects sufficiently to engage a cam 5^g on or attached to the frame 1 adjacent the path of the fingers 4^c. The cam 5^g is so disposed and of such length that the gripper will be opened before the fingers 4^c reach the fingers 2^c, and will close immediately after the fingers 4^c begin to take the slug away from the fingers 2^c, and hold the slug firmly while the slug is being taken and while it is making an impression; then 45 the gripper will be opened so as to release the slug, and may remain open until another slug is taken from the fingers 2^c.

These slugs, if desired, may be inked before being introduced into the chute so that they will not require any inking in the machine; or they may be inked by any suitable means after they are taken from the galley by the carrier 4^c and before reaching the printing point. As shown an inking roll 6 is provided, which roll may be a self inking roll, or any well known type, or as indicated in the drawing, it may be an inking fountain roll 6^b in the well known manner.

50 Afforded, suitable means may be provided for preventing the slug falling off the carrier under the action of centrifugal force. The gripper 5 would eliminate printing this; but as an additional protection, a curved finger 7 or bar 10 could be ar-

ranged at each side of the carrier between the slug taking point and the printing point as indicated in Fig. 1, so as to effectively prevent the slugs becoming displaced radially by centrifugal force.

55 After being inked the slug is carried on by the carrier to the point of impression. After the impression is made the gripper 5^a is caused to release the slug by suitable means; as by the rod 5^f engaging the end 75 of the cam 5^g, and it can be held open until the slug carrier takes another slug from the fingers 2^c.

As soon as the gripper releases the slug the latter would naturally be discharged by 80 gravity aided by centrifugal force into a slug funnel or guide 8, by which it is directed into a receiving chute 8^a, in which the slugs are received face down and from which chute the slugs can be directed into 85 removable galleys which can be attached to the outer end of the receiving chute in the usual manner, as in type setting machines and addressing machines using slugs.

90 The slugs may be moved forward in the chute 8^a by suitable means; as by packing lever 8^b mounted on a rock shaft 8^c, journaled in the frame 1 and having a crank arm 8^d engaging a cam 8^e on the shaft 4^b.

95 Any suitable means may be provided for 95 positively discharging the slug from the carrier after printing. As shown I have provided curved finger or fingers 8^f, which may be attached to any suitable support or to the receiving chute, as indicated in Fig. 100 1, and which fingers project into annular grooves 4^g in the periphery of the member 4, and between the fingers 4^c, so that as the member 4 rotates the fingers 8^f will cause the slugs to slide radially off the fingers 4^c 105 into the receiving chute; said fingers 8^f may be arranged at the receiving end and above the mouth of the receiving chute so as to direct the slugs discharged from the carrier 4 into the galley.

110 The addressing apparatus is especially designed and adapted for use in connection with printing presses and to address newspaper, or other printed articles as they are printed on the machine; and therefore in the 115 example shown the frame 1 is so constructed that it can be readily attached to part of the printing press; and preferably in such position that the carrier will cause the slugs to print the web or sheets demanding the folder 120 (shown at 1^a of such machine). In Fig. 5 of the drawings I have illustrated part of a web printing newspaper press to which the invention is applied; it should be understood however that the press may be a rotary, flat 125 bed, or other type of press.

130 In Fig. 5 I have illustrated diagrammatically an ordinary rotary web perfecting cylinder 1^b and an ordinary web folder 1^c (shown at 1^d). The web W after 130

being printed is led in the usual manner, according to the make of press, to the former F, and the addresses are applied thereto as it descends the former. Then the 5 web is folded between the first fold rolls R, and passed on to the final folding, cutting and collecting mechanisms, not shown, as usual.

F designates the folder former of the 10 printing press; R the usual roller mounted on a shaft S at the top of the former and rotated as usual to assist the web of paper W to and over the former. The shaft S is driven by gearing (not shown), and above 15 the shaft S is a tie rod T, which usually carries spring pressed rollers, which hold the web W in contact with the roller R at the top of the former. Below the shaft S is a bar or rod B which supports the upper 20 end of the former F. All of these parts are of ordinary construction and arrangement and are well known, and will be readily understood.

In the particular embodiment of the invention illustrated the addressing attachment frame is connected with and supported by the rods T and B and supporting frame 1; and for this purpose is shown as provided with an arm 1^a, which is secured by a split 25 collar 1^b and bolts 1^c to the rod T, and its base member 1^d is supported upon the tie bar B and detachably attached thereto by clamping bolt 1^e, as indicated in the drawing.

35 The shaft 4^b is so mounted adjacent the former and the length of the slug carrier so proportioned that during the rotation of the carrier the slug will be inked and then brought into contact with the web of paper 40 W passing down the former F and print the address upon the paper W preferably in the margins between successive impressions.

The shaft 4^b is rotated, as hereinafter described, at such speed that the speed of 45 movement of the face of the addressing slug carried by carrier 4 equals the speed of travel of the paper over the former, and the impression is therefore made on the moving web by the moving slug. To prevent injury 50 to the slug or to the web during the impression I preferably cut a small opening in the former F at the point of impression and mount an impression roller 7 at this point beneath the face of the former, so that the 55 impression will be actually made upon the paper while it is traveling by a traveling slug—and an impression roller which may be rotated by friction.

The shaft 4^b may be driven by any suitable means when the invention is embodied 60 in a separate addressing machine or by any suitable driving connection with some driven part of the machine to which the addressing mechanism is attached. When 65 applied to a printing mechanism the parts

should be so driven and the gearing so proportioned that the slugs A on the carrier will be moving at the printing point at the same speed as the paper or article to be impressed passing such point. 70

In the example shown, the shaft 4^b carries a gear 4^c which meshes with a gear 4^d attached to and driven by the shaft S; and the gears 4^c and 4^d are so proportioned that the slug carrier will be rotated once for 75 each newspaper or impression on the paper, when applied to a printing press, and the parts adjusted so that the different addresses will be successively printed upon the paper, preferably in the margins between successive 80 impressions thereon, so that each newspaper as it passes over the former has the address of the individual for whom it is intended printed upon it before it reaches the folder rolls. 85

When the device is used as an attachment for printing presses the gear 4^c can be split and bolted to the shaft S and the frame 1 attached to the tie rod T and bar B as described, to position the addressing mechanism beside the former; and the impression roller 7 can be attached to the under side of the former in the proper position. 90

When such an addressing attachment is applied to a printing press the papers can 95 be delivered therefrom addressed to different parties or destinations, ready for mailing; and the necessity for subsequently addressing such papers, or passing such papers through an addressing machine is avoided; 100 as well as the loss of time required for such operations; and the expense entailed in operating a separate addressing machine is eliminated. The addresses are preferably applied to the margin of the page of the 105 newspaper which will be outermost when folded, and customarily the press is so threaded that the outermost page is on the outside layer of paper passing over the former so that no rearrangement of the 110 forms in the press would be ordinarily necessary in order to use the attachment therewith.

By locating the addressing attachment at 115 the former and printing the addresses upon the papers as they pass over the former the attachment is in the most convenient place for operation upon the paper; the addressing devices can be readily adjusted to correctly print upon the margins whenever the 120 papers are being properly delivered to the folding rolls; and the addressing apparatus is not in the way when it is necessary to thread the press or folder, in making ready the press, or in case of rupture of the web. 125 Other advantages of the invention when used as an addressing attachment for printing presses will be readily appreciated by those familiar with the art.

The addresses are printed upon the web 130

of paper after it is printed and before it is severed, and between the printing mechanism and the web severing mechanism, so that no auxiliary mechanism for handling 5 the web or the addressing mechanism is required.

While I have described the invention as embodied in an attachment for web printing presses and applied to such presses it 10 will be obvious to those skilled in the art that the invention could be readily embodied in a separate machine for addressing letters, envelopes, packages, and the like. In such case the frame would be properly modified, 15 and means provided for rotating the shaft 4^b manually or by power, all of which will be readily understood and provided by those familiar with the art.

I claim:

- 20 1. In an addressing apparatus; a feed chute for individual printing members; means for successively ejecting printing members from said chute; spaced fingers projecting beyond the chute onto which the printing members are ejected; and a carrier having spaced fingers adapted to take an ejected printing member from the chute fingers and carry it past the point of impression; substantially as described.
- 25 2. In an addressing apparatus; a feed chute for individual printing members; means for successively ejecting printing members from said chute; spaced fingers projecting beyond the chute onto which the printing members are ejected; and a carrier adapted to take an ejected printing member from the said fingers and carry it past the point of impression; substantially as described.
- 30 3. In an addressing apparatus; a feed chute for individual printing members; means for successively ejecting printing members from said chute; spaced fingers projecting beyond the chute onto which the printing members are ejected; and a carrier adapted to take a printing member from the said fingers and carry it past the point of impression; with means on said carrier for holding the printing member; means for 35 releasing the printing member after the printing operation; and means for receiving the discharged printing member.
- 40 4. In an apparatus of the character specified, a feed chute for the printing members; means for successively ejecting printing members from the chute; spaced fingers projecting to one side of the chute and upon which the printing members are ejected; and a carrier having spaced fingers adapted 45 to pass between the supporting fingers and remove the ejected printing member therefrom; substantially as described.
- 50 5. In an apparatus of the character specified, a feed chute for the printing members; means for successively ejecting printing members from the chute; spaced fingers projecting to one side of the chute and upon which the printing members are ejected; and a carrier having spaced fingers adapted 55 to pass between the supporting fingers and remove the ejected printing member therefrom; substantially as described.
- 60 6. In an apparatus of the character specified, a feed chute for the printing members; means for successively ejecting printing members from the chute; spaced fingers projecting to one side of the chute and upon which the printing members are ejected; and a carrier having spaced fingers adapted 65 to pass between the supporting fingers and remove the ejected printing member therefrom; substantially as described.

members from the chute; spaced fingers projecting to one side of the chute and upon which the printing members are ejected; and a carrier having spaced fingers adapted to pass between the supporting fingers and remove the ejected printing member therefrom; with means on said carrier for holding the printing member during the printing operation, and means for releasing the printing member after the printing operation. 70

6. In apparatus of the character specified, a feed chute for printing slugs; a reciprocating ejector for successively ejecting slugs from the chute; spaced supporting fingers 80 projecting to one side of the chute and upon which the slugs are ejected; a slug carrier having spaced fingers adapted to pass between the supporting fingers and remove the ejected slug therefrom; means on said carrier for holding the slug during the printing operation, means for causing the gripper to release the slug after the printing operation; a receiving chute for released slugs, and means for packing the slugs in 85 the receiving chute.

7. In an addressing apparatus, the combination of a feed chute; spaced supporting fingers projecting from the feed chute; means for ejecting printing members successively from said chute onto said fingers; a rotatable slug carrier provided with spaced fingers adapted to pass between the slug supporting fingers and remove a slug therefrom; means for holding the printing member on the carrier during the printing operation; means for releasing the printing member after the printing operation; stripping fingers adapted to pass between the fingers on the carrier and discharge the printing 95 member from the carrier after the printing operation; a receiving chute for the discharged printing members; and means operated from the slug carrier shaft for packing the printing members in the receiving 100 chute.

8. In an addressing apparatus the combination of a feed chute; spaced fingers projecting from this chute; means for ejecting slugs successively from the chute onto said 105 fingers; a rotatable carrier having circumferential grooves and provided with spaced fingers adapted to pass between the slug supporting fingers and remove a slug therefrom; a clamping member mounted on the 110 slug carrier adapted to grip the slug as it is taken from said supporting fingers and hold it during the printing operation; means for causing the clamp to release the slug after the printing operation; and stripping fingers 115 engaging said grooves to discharge the slug from the carrier after the printing operation.

9. In an addressing apparatus, the combination of a feed galley for slugs; spaced 120

125

supporting fingers projecting from the feed galley; a slide for ejecting slugs successively from the galley onto said fingers; a rotatable shaft adjacent the said galley; a circumferentially grooved slug carrier mounted on said shaft and rotatable therewith and provided with spaced fingers adapted to pass between the slug supporting fingers and remove a slug therefrom; means for holding the slug on the carrier during the printing operation; means for releasing the slug after the printing operation; and stripping fingers engaging said grooves and adapted to pass between the fingers on the carrier and discharge the slug from the carrier after the printing operation.

10. In an addressing apparatus the combination of a feed galley for slugs; spaced fingers projecting from this galley; means for ejecting slugs successively from the galley onto said fingers; a slug carrier provided with spaced fingers adapted to pass between the slug supporting fingers and remove a slug therefrom; means mounted on the slug carrier to clamp the slug during the printing operation; means for opening the clamp to release the slug after the printing operation; a receiving galley for the discharged slugs; a lever for packing the slugs in the receiving galley, and a cam on the slug carrier shaft for operating said lever.

11. In an addressing apparatus the combination of a feed galley for slugs; spaced fingers adjacent this galley; a slide for ejecting slugs successively from the galley onto said fingers; a rotatable shaft adjacent the said galley; a slug carrier mounted on said shaft and rotatable therewith and provided with spaced fingers adapted to pass between the slug supporting fingers and remove a slug therefrom; a clamping member mounted on the slug carrier adapted to grip the slug as it is taken from said supporting fingers and hold it during the printing operation; means for causing the clamp gripper to release the slug after the printing operation; stripping fingers adapted to pass between the fingers on the carrier and discharge the slug from the carrier after the printing operation; a receiving galley for the discharged slugs; and means for packing the slugs in the receiving galley.

12. In combination with printing mechanism and folding mechanism having a former; of means opposite and co-operating with the former for applying different addresses to different impressions on the paper as it descends the former.

13. In combination with printing mechanism and folding mechanism having a former, of means opposite and co-acting with the former for applying different addresses on the margins of successive impressions on the paper as it descends the former.

14. In combination with a web printing

mechanism and web folding mechanism having a former, of means opposite and co-acting with the former for applying addresses on the margins of successive newspaper impressions on the web while it is passing over the former.

15. In combination with printing mechanism and folding mechanism having a former over which the printed web is passed; of means opposite and co-acting with the former for applying different addresses to successive newspaper impressions on the web as it passes down the former.

16. In combination with web printing mechanism and folding mechanism having a former over which the web is passed; of means beside the face of the former for applying different addresses to different newspaper impressions on the web while the web is passing over the former.

17. In combination with web printing mechanism and folding mechanism having a former over which the web is passed; of means opposite and co-acting with the former for printing different addresses on the margins between successive newspaper impressions on the web while the web is passing over the former.

18. In combination with printing mechanism and folding mechanism having a former, means in front of the former for applying addresses; and means in rear of the face of the former and co-operating with the address applying means to apply addresses to the paper as it descends the former.

19. In combination with printing mechanism and folding mechanism having a former of means in front of the former for printing addresses on the paper; and impression means in rear of the face of the former and co-operating with the printing means to impress the paper passing therebetween as it descends the former.

20. In combination with printing mechanism and folding mechanism having a former of means in front of the former for printing addresses on the paper; and a roller connected with the former opposite the printing means and co-operating with the printing means to print addresses on the web as it passes down the former.

21. In combination with printing mechanism and folding mechanism having a former; of means in front of the former for printing addresses, and an impression roller in rear of the former opposite the printing means, and co-operating with the printing means to print addresses on different newspaper impressions on the web of paper as it descends the former.

22. In combination with printing mechanism and folding mechanism having a former; of an addressing mechanism comprising a carrier in front of the former

- adapted to carry a printing member and impress it against the paper descending the former and then discharge it; means for receiving discharged printing members after printing; and means for operating the addressing mechanism in time with and from the mechanism of the printing press.
23. In combination with printing mechanism and folding mechanism having a former; an addressing mechanism comprising a carrier in front of the former adapted to carry a printing member and impress it against the paper as it descends the former; means for feeding printing members to said carrier; means for releasing the printing member after the impression; and impression means in rear of the former face co-acting with the printing members to print the web as it descends the former.
24. In combination with printing mechanism and folding mechanism having a former; an addressing mechanism comprising a carrier in front of the former adapted to carry a printing member and impress it against the paper as it descends the former; means for feeding printing members to said carrier; means for causing the said carrier to hold the printing member until the impression has been made; means for releasing the printing member after the impression; and impression means in rear of the former face co-acting with the printing members to print the web as it descends the former.
25. In combination with printing mechanism and folding mechanism having a former; of an addressing mechanism comprising a carrier in front of the former adapted to carry a printing member and impress it against the paper descending the former; means for feeding printing members to said carrier; means for causing the said carrier to hold the printing member until the impression has been made; means for releasing the printing member after the impression; and impression means in rear of the former face co-acting with the printing members to print the web as it descends the former.
26. In combination with the printing mechanism and folding mechanism having a folder former, and a driven shaft, at the top of such former; of an addressing mechanism adjacent the former, comprising a carrier adapted to carry a printing member and impress it against the paper descending the former; means for feeding printing members to said carrier; means for causing the said carrier to hold the printing member until the impression has been made; means for releasing the printing member after the impression; and gearing between the said shaft and the addressing mechanism to operate the latter.
27. In combination with printing mechanism and folding mechanism including a folder former, and a driven shaft at the top of such former; of means for printing upon the web or sheets descending the former, comprising a carrier adapted to carry a printing member and impress it against the paper descending the former; an impression member beside the former co-operating with the printing member; means for feeding printing members to said carrier; means on said carrier to hold the printing member until the impression has been made; means for causing said holding means to release the printing member after the impression; means for receiving discharged printing members after printing, and gearing between the said shaft and the addressing means to operate the latter.
28. In an addressing apparatus, the combination of a feed chute; spaced supporting fingers adjacent the chute onto which the printing members are ejected; means for ejecting printing members successively from the chute onto said fingers; a rotatable carrier provided with spaced fingers adapted to pass between the slug supporting fingers and remove a printing member therefrom; a gripper pivotally attached to one side of said member adapted to clamp the slug when taken by the fingers; and means for releasing the printing member after the printing operation; and stripping fingers adapted to discharge the printing member from the carrier after the printing operation.
- In testimony that I claim the foregoing as my own I affix my signature.
- PAUL F. COX.
